UNITED STATES PATENT OFFICE

2,550,437

SELF-CLOSING BILLHOLDER

Maurice M. Yates, Greenville, Tenn.

Application March 29, 1947, Serial No. 738,153

4 Claims. (Cl. 150—38)

1

My invention relates to a new and useful improvement in billfolds, and has for its object the providing in a billfold of a currency section, the back and cover of which are hinged together with elastic members in such manner that the cover of this currency section will automatically close itself when not in use, which currency section will be small and compact enough to be conveniently combined with a coin holder, or other time saving devices or conveniences for holding coins, stamps, pictures or other small articles, all together in one unit, and in the currency section a means of automatically securing in position in the billfold such articles as paper currency.

An embodiment of the invention is shown in the drawings which form a part of this specification, and in which,

Fig. 1 is a perspective view of the billfold with the coin holder swung to the right, and over the receptacles for extra coins and other small articles, and with the cover of the currency section swung open to the left.

Fig. 2 is a top plan view of the billfold when closed.

Fig. 3 is a cross-sectional view of the billfold taken on line A—A of Fig. 1, with the position of some of the parts changed slightly so as to provide a better illustration of the construction of the billfold.

Fig. 4 is a cross-sectional view of the left segment, or currency section of the billfold taken on line A—A of Fig. 1, showing the cover of the currency section swung to the left.

Fig. 5 is a cross-sectional view of the left segment, or currency section of the billfold taken on line A—A of Fig. 1, showing the cover of the currency section swung to the right.

The currency section comprises a stiff back 4, and a stiff cover 5 fastened together with elastic members 7 and 8. The cover and back are in the nature of flat pieces of any suitable stiff material. Members 7 and 8 are in the nature of elastic tape, or any material or substance capable of recovering size and shape after deformation. The back 4 is fastened to the billfold cover 1 by sewing or any other suitable means. One end of each member 7 is fastened to the inside face of cover 5 at a point a short distance from the edge by means of stitching 7a, as indicated in Fig. 5, the opposite ends being attached to back 4 at or near the edge. One end of each member 8 is fastened to the inside face of cover 5 on the opposite side from which members 7 are fastened and at a point a short distance from the edge by means of stitching 8a, as indicated in

2

Fig. 4, the opposite ends being fastened to back 4 at or near the opposite edge from which the ends of members 7 are fastened. Members 7 and 8 are fastened a distance back from the edge of cover 5 to provide leverage in pulling the cover toward and against the back.

The result of the foregoing construction is that one set or the other of elastic members 7 and 8, because of the manner in which they are attached to the back and cover, and because of their having properties of elasticity, will be extended when the cover is swung open in either direction; therefore, one or the other of the two sets of elastic members will always tend to pull the back and cover toward and against each other, face to face, when they are opened, or separated; also these members acting together, act to hinge the back and cover at both edges, permitting opening of the cover either to the right, or to the left; furthermore, because of the manner in which the back, cover, and the four elastic members are connected together, they will operate to produce the result that when the cover is opened in either direction, and a folded bill placed between the back and cover, then the cover folded down upon the bill, then folded once again in the same direction, that the bill will be drawn under either members 7, or members 8, depending on the direction of the folding of the cover. Additional bills may be added to the bills already under either of the two sets of elastic members 7 or 8. For example, if it is desired to add more bills to those held against the cover 5, the cover is opened to the left as shown in Fig. 1, the bill or bills placed between the back and cover, and over members 8, when the cover is folded down upon the bill or bills, then folded once again to the right. If it is desired to add more bills to those held against the back 4, the cover is opened to the right, the bill or bills placed between the back and cover and over members 7, then the cover is folded down upon the bills, then folded once again to the left. All bills will be maintained in their separated positions upon all further opening or closing of the cover.

The right segment of the billfold is composed of a holder 9 for coins 12 which is fastened by eyelets 11 to part 6 which is fastened between back 4 of currency section and billfold cover 1, as illustrated in Figures 1 and 3, a container 13 for extra coins that cannot be placed in holder 9, and a container 14 for other small articles. The currency section and all other parts of the billfold are enclosed within a cover 1 and fastened by a slide fastener 2.

Particular advantages of this billfold are (1) that the cover of the currency section automatically closes itself and remains closed when not in use, (2) the currency section provides a very compact unit for holding paper currency, making it possible to combine this currency holder with other conveniences often desirable to have in a billfold, (3) the action of the elastic members in holding the back and cover close against each other provides additional protection against currency becoming detached from under these members, and (4) it provides a private compartment for currency assuring the user that any currency placed in the billfold will be hidden from inquisitive eyes when the billfold is opened to extract coins, or items other than currency.

While I have illustrated and described the preferred form of my invention, I do not wish to limit myself to the precise detail of structure shown, but desire to avail myself of such variations and modifications as come within the scope of the appended claims.

Having thus described my invention, what I claim as new and desire to secure by Letters Patent is as follows, express reservation being made of permissible modifications:

1. In a billfold, a stiff, flat, back member and a stiff, flat, cover member connected to one another swingably in either direction around a lateral edge as an axis by means of a plurality of transverse flexible elastic tapes attached to the back and cover members, each tape being attached adjacent to a lateral edge of the back member; then passing across an inner face and being attached to the inner face of the cover member a short distance away from the opposite lateral edge of the cover member.

2. In a billfold, a stiff, flat, back member and a stiff, flat, cover member connected to one another swingably in either direction around a lateral edge as an axis by means of a plurality of transverse flexible elastic tapes attached to the back and cover members, each tape having one end attached to the outer face of the back member adjacent to a lateral edge thereof, then passing over the edge and transversely back across an inner face and having its other end attached to the inner face of the cover member a short dis-

tance away from the opposite lateral edge of the cover member.

3. In a billfold, a stiff, flat, back member; a stiff, flat, cover member; and transverse flexible elastic tapes connecting the cover member to the back member, each tape being attached adjacent to a lateral edge of the back member, then passing across an inner face and being attached to the inner face of the cover member a short distance away from the opposite lateral edge of the cover member, at least two of said tapes being attached adjacent to one lateral edge of the back member and at least two tapes being attached adjacent to the opposite lateral edge of said back member.

4. In a billfold, a stiff, flat, back member; a stiff, flat, cover member; and two pairs of transverse flexible elastic tapes connecting the cover member to the back member, each tape having one end attached to the outer face of the back member adjacent to a lateral edge thereof, then passing over the edge and transversely back across an inner face, and having its other end attached to the inner face of the cover member a short distance away from the opposite lateral edge of the cover member, one pair of said tapes being attached adjacent to one lateral edge of the back member and the other pair of tapes being attached adjacent to the opposite lateral edge of said back member.

MAURICE M. YATES.
